(57) **CLAIM**

I claim the ornamental design for a set of two identical tote components for dragging a game carcass, substantially as shown and described.

DESCRIPTION

FIG. 1 is a perspective view of a set of two identical tote components showing my new design;

FIG. 2 is a top view of one of the two identical components, it being understood that a bottom view is identical thereto;

FIG. 3 is a rear view thereof;

FIG. 4 is a front view thereof; and,

FIG. 5 is a right end view thereof, it being understood that a left end view is identical thereto.

References used herein as front, rear, left, right, top and bottom of the claimed design are not meant for any particular in-use orientation and may be changed for different orientation of the claimed design as chosen by the user.
